Patented June 9, 1914.

UNITED STATES PATENT OFFICE.

ALANSON L. FISH, OF FLUSHING, NEW YORK.

RELAY-RACE STARTER.

1,099,244.

Specification of Letters Patent.

Patented June 9, 1914.

Application filed May 31, 1913. Serial No. 771,073.

To all whom it may concern:

Be it known that I, ALANSON L. FISH, a citizen of the United States, residing at Flushing, county of Queens, State of New York, have invented a new and useful Relay-Race Starter, fully described in the following specification and the accompanying drawing, forming a part of the same.

My invention relates to a new relay race 10 starter.

The object of the invention is to provide a machine which will automatically give a starting signal to a succeeding runner of a team, the instant the preceding runner 15 reaches a predetermined point.

The invention is particularly useful in races where the succeeding runner starts from a point other than the finishing mark of the preceding runner, and at the time 20 when said preceding runner reaches said finishing mark.

With this and other objects in view, the invention consists in certain combinations and parts as will be hereinafter fully described and then specifically pointed out.

Referring to the drawing:—Figure 1 is a side elevation of a mechanism in which my invention may be embodied. Fig. 2 is a plan view of the same. Fig. 3 is a perspective view of the upper portion of the device, showing the parts in their normal position. Figs. 4 and 5 illustrate details. Fig. 6 is a fragmentary perspective view of some of the parts illustrated in Fig. 3, but in the 35 position which they assume when the device is actuated.

Reference letter S represents the weighted base of the device. This base is of elliptical shape and has its weight concentrated for the most part around its edge in order to steady the superstructure which it supports. Rising from the base is the vertical hollow standard R, which is provided at its upper extremity with a rigid collar P. The collar P has a threaded aperture for the reception of the set-screw O. The rod C is adapted to be vertically adjusted in the standard R and secured in adjusted position by means of the set screw O. The sleeve B is adjustably secured to the upper end of the rod C, by means of the set-screw H. The member H serves also as a pivot for the signal arm E. The arm E is provided at its upper end with a suitable flag or signal M, and at its lower end with a weight D, the latter being for the purpose of normally holding the signal arm in a substantially vertical position. The center of gravity of the weight D is however somewhat to the right (as viewed in Fig. 1) of the center line of the signal arm D, for a purpose which will presently appear. The chest arm A is provided at one end with the apertured bifurcations 1, 2, whereby the arm is mounted to swing above the rod C, but is prevented from moving longitudinally with respect thereto by reason of the sleeve B as shown in Fig. 3. This end of the arm A is also provided with a web J, which is adapted to contact with the shoulders N, Z of the sleeve B to limit the swinging movement of the said arm. The other end of the arm A is provided with an angularly adjustable extension I, adapted to be secured in adjusted position by the set-screw T. Secured to the part 1 of the arm A, by means of the set-screw G, is the cam-like roll F.

The operation of the device is as follows: In their normal positions the various parts appear as shown in full lines in Figs. 1 and 3. The chest arm A is in its extreme position with the web J in contact with the shoulder Z. The signal arm E is in substantially vertical position and contact of the upper part of this arm with the cam-like roll F is assured by the heretofore mentioned eccentricity of the center of gravity of the weight D. Such eccentricity causes the upper part of the arm E to swing slightly to the right of the vertical (as shown in Fig. 1). The various parts are adjusted so that the extension L of extension I of the chest arm A, will project out over the running track at such a height that it will be struck by the chest of a passing runner. The purpose of the angular adjustment of the extension I of the chest arm is so that extension L of extension I may be placed squarely in the path of the runner even though the device is placed at a curve in the track. The device is, of course, positioned at the finish line of the individual relays. As a runner crosses the finish line, his chest hits the extension L of extension I of the chest arm, thereby swinging the said arm quickly about the rod C as an axis. As a result the cam-like roll F, which is secured to the chest arm, has a camming action on the upper part of the signal arm E, whereby the latter is given a rapid counter-clockwise swinging movement about its pivot H, the parts assuming the positions

indicated by the dotted lines in Figs. 1 and 3, and by full lines in Fig. 6. This swinging of the signal arm E is the starting signal for the succeeding runner of the team.

5 As soon as the preceding runner has passed, the parts immediately resume their normal positions by reason of the weight D.

The invention is not limited to the particular embodiment herein shown and described, but obviously many changes may be made therein without departing from the spirit of the invention.

What I claim is:

1. In a relay race starter, the combination of a signal, actuating means therefor, said means being operable by contact with the body of a passing runner, and means for automatically returning the signal to its original position.

20 2. In a relay race starter, the combination of a pivoted signal arm, a pivoted actuating arm therefor, said actuating arm being adapted to be operated by contact with the body of a passing runner, and means 25 for automatically returning the signal arm to its original position.

3. In a relay race starter, the combination of a pivoted signal arm, a cam-like roll for actuating said arm, and a second arm to which said roll is connected, said second arm being positioned in the path of a passing runner so that it will be struck by the passing runner and the signal arm thereby actuated.

35 4. In a relay race starter, the combination of a pivoted signal arm, a cam-like roll for actuating said arm, and a second arm to which said roll is connected, said second arm being positioned in the path of a passing runner so that it will be struck by the passing runner and the signal arm thereby actuated, and said signal arm being provided with a counterweight, to immediately return said arms to their original positions.

45 5. In a relay race starter, the combination of a signal arm pivotally mounted about a horizontal axis, a counterweight secured to one end thereof to normally hold said

arm in a substantially vertical position and a chest arm pivotally mounted about a vertical axis and provided with means for swinging said signal arm about its pivot.

50 6. In a relay race starter, the combination of a signal arm pivotally mounted about a horizontal axis, a counterweight secured to one end thereof to normally hold said arm in a substantially vertical position, a chest arm pivotally mounted about a vertical axis and provided with means for swinging said signal arm about its pivot, 60 and means to limit the pivotal movement of said chest arm.

7. In a relay race starter, the combination of a signal arm, a support therefor, said support being vertically adjustable, and 65 a second arm mounted adjacent said support for actuating said signal arm, said second arm being adapted to be operated by contact with the body of a passing runner.

8. In a relay race starter, the combination 70 of a signal arm, a support therefor, said support being vertically adjustable, a second arm mounted adjacent said support for actuating said signal arm, and an angularly adjustable extension secured to said second 75 arm, said extension being adapted to be moved by contact with the body of a passing runner to thereby actuate said arms.

9. In a relay race starter, the combination 80 of a vertically adjustable support, a signal arm pivotally mounted on said support, so as to swing about a horizontal axis, a chest arm adjacent said support and adapted to swing about a vertical axis, an actuating roll secured to said chest arm, said 85 signal arm being provided at its lower end with an eccentrically mounted weight, whereby the upper portion of said signal arm is maintained in contact with said actuating roll and movement of the chest arm 90 effects simultaneous movement of the signal arm.
